(57) **CLAIM**

The ornamental design for a stand for planar article, as shown and described.

DESCRIPTION

FIG. 1 is a perspective view of the stand for planar article of the present design;

FIG. 2 is a top view thereof;

FIG. 3 is a side view with the opposite side being a mirror image thereof;

FIG. 4 is a bottom view thereof;

FIG. 5 is a front view thereof;

FIG. 6 is a back view thereof;

FIG. 7 is a perspective view with planar article in landscape orientation;

FIG. 8 is a perspective view with planar article in portrait orientation;

FIG. 9 is a top view of the stand for planar article in a closed position; and,

FIG. 10 is a bottom view of the stand for planar article in a closed position.

The planar article shown in broken lines forms no part of the claimed design.
